INERTIA MEMBER

Ernest Wildhaber, 124 Summit Drive, Rochester, N.Y.

Filed Mar. 14, 1955, Ser. No. 494,076

24 Claims. (Cl. 74—50)

The present invention relates to a rotary inertia member for steadyng a rotary part under a periodically-repeating, varying load. In another aspect, the invention relates to an inertia member that is combined with a mass-balancing member, for steadyng the motion of a rotary part, and for achieving mass balance in a reciprocating part driven by said rotary part.

One object of the present invention is to provide a rotary inertia member for storing up kinetic energy, and alternately transmitting energy to and receiving energy back from a rotary part under repeating varying load, where the inertia member is so connected to the rotary part that it has much larger fluctuations in speed than the rotary part itself.

Another object of the invention is to provide a rotary inertia member that is connected to a timing train which operates with repeating varying motion, so that the change of kinetic energy is supplied directly by said inertia member and does not disturb the timing.

Another object of the invention is to provide an improved reciprocating device adapted to operate smoothly at high speed.

Another object of the invention is to provide a reciprocating device equipped to achieve mass balance while completely avoiding all of the usual drawbacks of mass balance. Ordinarily the big price to be paid for mass balance is increased inertia of the parts, which causes the required torque to fluctuate still more.

Another object of the present invention is to provide an inertia member which is disposed adjacent the place where it is needed so that kinetic energy flows from the inertia member upon acceleration of the part to which the inertia member is connected, and flows back again to the inertia member when the parts are decelerated. In this way, the variation of the torque supplied from the outside is kept at a minimum.

Another object of the invention is to provide an oscillating device containing an inertia member, so that the torque input fluctuates little or not at all.

A further object of the invention is to provide an inertia member in a repetitive motion device, especially in a device with a constant speed portion, and to constrain the inertia member in such way that the inertia member provides a substantially constant load in the constant speed portion of the motion of the device, somewhat like a brake, to avoid backlash.

Another object of the invention is to provide a reliable index mechanism which can be operated faster than heretofore possible and with maximum smoothness.

Another object of the invention is to provide an index mechanism which can be operated reliably at high speed by supplying the energy for acceleration by an inertia member adjacent the index mechanism, which takes back the energy again at deceleration.

Other objects of the invention will be apparent herein-after from the specification and from the recital of the appended claims.

Fig. 34 is a cylindrical section developed to a plane, the section being along the cylindrical surface described by the axis of the actuating roller or pin of the rotary part shown in Fig. 30, as the part rotates, and further showing the stationary guideways controlling the axial motion of the part;

Fig. 35 is a section on the line 35—35 of Fig. 30 looking in the direction of the arrows; and

Fig. 36 is a diagram illustrating a modified way of changing the inertia effect of the inertia member.

Referring first to the embodiment of the invention illustrated in Figs. 1 to 10, 40 denotes a rotary face plate to which is rigidly secured a shaft 41. The face plate and shaft are journaled in spaced anti-friction bearings 42 and 43. Bearing 42 is a cylindrical roller bearing supporting the face plate around its periphery; and bearing 43 is applied to the free end of the shaft 41 and is adapted to take axial thrust loads in both directions as well as radial load.

Mounted on the face plate 40 and adjustable radially of the axis of the face plate is a slide 44 (Fig. 1) which carries a crank pin 45 on which a sliding block 46 is rotatably mounted. The latter engages a straight slot 47 (Fig. 2) of a slide 48. This slide is made of two parts 48', 48'' which are adjustable relative to each other in the direction of the slide motion. The slide may carry a cutting tool or a grinding wheel. In Fig. 1 the slide is shown as carrying a gear cutting tool 50 which is adapted to cut a cylindrical gear blank 51.

Rotation of the face plate 40 causes the crank pin to move in a circle 49 (Fig. 2) and reciprocates the slide 48 along guide rails 52 which are rigidly secured to the machine frame by screws (not shown) which pass through holes 54 in the guide rails.

The face plate 40 may be rotated either at constant or at varying speed. In the embodiment illustrated it is driven at a speed varying in such a manner that the velocity of the slide 48 is constant in one direction of stroke, namely, the downward direction. This is accomplished by a varying ratio drive consisting of a cylindrical pinion 55 and a mating face gear 56 (Figs. 1 and 7). The pinion 55 is rotated at a uniform velocity by applying uniform motion to the helical gear 57, which is rigid with the pinion 55. The face gear 56 has teeth 58 (Fig. 7) arranged along a closed curve 60 which extends about the gear axis 41', which is also the axis of shaft 41, at a varying distance therefrom. The varying ratio pair may be of the character fully described in my copending application Serial No. 431,733, filed May 24, 1954, now Patent No. 2,770,973, granted November 20, 1956. A drive of this kind will drive slide 48 at a constant velocity in one direction, except at the ends of the stroke near the reversal; and it will give a quick return motion.

The quick return motion increases the inertia loads. They are considerable, especially at high speed operation.

They tend to shake the whole device and to produce vibration. Mass balance is achieved in the present invention in such way that it will function exactly at all lengths of stroke without adjustment.

For this purpose, a counter-balancing slide 62 is provided which is driven from the slide 48 to move in the opposite direction. It is driven through non-metallic friction rollers 63 (Figs. 2 and 6) and gears 64 coaxial therewith. Each friction roller 63 is mounted on the hub 10 portion of a gear 64 to rotate therewith. Each gear 64 is set in an opening of one of the guide rails 52 and is rotatably mounted on a pin 65 held in a bore extending through the guide rails. Each gear 64 meshes with a pair of racks 66 and 67 which are rigid with the slides 48 and 62, respectively. Motion of the slide 48 turns the gears 64 through the racks 66; and the gears 64 move the slide 62 at the same rate in the opposite direction through the racks 67.

The friction rollers 63 engage plane surfaces provided 20 on the sides of the racks and rigid with the racks. These plane surfaces may coincide with the pitch planes of the racks. In ordinary operation, the drive is through the friction rollers, backlash being provided in the gear and racks. The positive drive is for safety.

To obtain perfect mass balance, the counter-balance slide 62 should have the same mass and weight as the slide 48 when its rate of motion is, as indicated, equal to the rate of motion of the slide 48. Also the straight line described by their centers of gravity of the two slides 30 should be the same on both slides, that is, their centers of gravity may be displaced from each other only in the direction of slide motion. In a view taken in the direction of slide motion the centers of gravity should appear as coinciding.

This position of the center of gravity of the slide 62 is accomplished by making the slide 62 reach over the slide 48, as shown in Fig. 1, and by having its main mass on the sides 68 on the level of the slide 48. Slide 62 is disposed more toward one end of the guide rails 35 52, that is, toward their upper ends. It engages the same guide rails as the slide 48 but from the outside while the slide 48 engages them from the inside.

The unit, comprising the face plate 40, the shaft 41, and the parts attached to them, turns at a varying speed 45 so that a varying unbalanced inertia moment results. Ordinarily this has no ill effects because of the relatively small moment of inertia of the unit. If on large machines it is desired to provide mass balance for this inertia moment, this can readily be done in accordance with the present invention.

The unit is geared at a constant velocity ratio to a member 70 which is rotatably mounted on a shaft 71 secured to the machine frame 53, and having an axis parallel to the axis of the shaft 41. The member 70 55 then rotates in the opposite direction as compared with the face plate unit, and has opposite inertia moments. For complete balance of the moments, the tooth ratio between the gear 73 and member 70 should be equal to the proportion of the moments of inertia of the face 60 plate unit and of the member 70. The heavier the member 70 is, and the larger its moment of inertia, the larger would be the gear reduction. The heavier member requires less energy for the same balance, as is readily understood. If the moments of inertia are equal, then 65 the same kinetic energy is stored up and released in the member 70 and the face plate unit.

Where the face plate unit is rotated at a uniform velocity to produce a harmonically varying slide velocity there is no need for a member 70.

Mass balance, important as it is for high speed operation, can have its drawbacks too. It increases the energy fluctuations and the torque fluctuations.

At the stroke ends the motion of slide 48 is zero so that the kinetic energy of the slide is zero. At mid-stroke, especially during the quick return stroke, the

velocity of the slide and its kinetic energy are a maximum. With mass balance the kinetic energy of the counter-balance slide 62 is added. When the velocity of slide 62 is equal and opposite to the velocity of the tool slide 48, then with equal mass its kinetic energy is also the same as the kinetic energy of the tool slide 48. In other words, in this case the balancing slide 62 adds one hundred percent to the torque variation. This may result in torsional vibration. It is particularly serious when the motion of slide 48 is a timed motion as where the uniform velocity portion of the cutting stroke of slide 48 is timed with the rotation of the gear blank 51 to cause the tool to cut helical teeth of a required helix angle on the gear teeth. Errors in timing are reflected in errors in the helix angle of the gear produced.

Accordingly, if nothing else were done, one evil would merely have been exchanged for another. With an inertia member built and connected in accordance with the present invention, however, not only are torsional deflections of the drive and of the timing train avoided in ordinary reciprocation without mass balance, but also the drawbacks of mass balance can be completely avoided. The inertia member stores up kinetic energy; it delivers the stored up energy; and it receives it back when needed. It acts directly on the face plate unit with a single mesh. The energy flows directly from the inertia member to the slides and from the slides to the inertia member, without going through a long and yielding timing train. It makes high speed operation with mass balance practical.

Reciprocating device with inertia member

A principal use of the inertia member of the present invention is to balance the variations of the kinetic energy.

Figs. 1 and 8 show how an inertia member 74 may be geared to the face plate 40 for this purpose. Mass member 74 is rigidly secured to a pinion 76 by involute splines 77 provided on the pinion member and by a nut 78 that threads onto the pinion member. The splines 77 are obtained by turning down or grinding down one end of the pinion teeth so that they have a smaller depth. Matching projections or internal teeth are provided in the hub of the mass member 74. Pinion 76 meshes with a face gear 75 at a varying velocity ratio. Face gear 75 is integral with a plate 79 that, in turn, is rigidly secured to the shaft 41. The pinion 76 with the mass member 74 is rotatably journaled in two bearings 80 and 81 in a flanged stationary part 82 secured to the machine frame.

The face gear 75 differs from the face gear 56 so that pinion 76 and mass member 74 turn at a varying speed. Just how the speed should vary will be described hereinafter.

The mass member 74 is intended for the slides 48 and 62. Once its motion has been correctly determined and provided, it will furnish and receive the varying kinetic energy of the slides 48 and 62 so that the kinetic energy flows back and forth, but remains constant for the unit including the slides and the mass member.

At a given stroke length an inertia member determined to exactly balance the varying inertia torque during the entire cycle of motion keeps this exact balance at all speeds. While the fluctuations of the kinetic energy of the slides 48, 62 increase with increasing number of turns per minute of the face plate 40 in proportion to the square of that number, the counterpart fluctuations of the kinetic energy of the mass member increase in the same way in proportion to the square of that number. In other words, the balance is not tied down to a given angular velocity.

When, however, the length of stroke is changed, the fluctuations increase on the slide; and it becomes desirable to make a change also in the mass member. In accordance with the present invention this may be done by changing the mass. The mass member comprises

discs 83 (Fig. 8) splined to its body portion 74', and secured against a shoulder thereon by nuts 84 that thread on screws 84'. To increase the energy fluctuations of the mass member, discs 83 are added; and to reduce these energy fluctuations, some of the discs 83 are removed. The inertia moment of a mass member providing exact balance at a given length of stroke should be doubled when the length of stroke is doubled, tripled when the length of stroke is tripled, halved when the

length of stroke is halved, etc.

In the diagrams, Figs. 9 to 11, the abscissa represents the turning angle of the uniformly rotating drive pinion 55 (Figs. 1 and 7), a complete turn of the face plate 40 being plotted. The middle corresponds to the middle position of the working stroke, its ends to the middle positions of the return stroke. Full line 85 represents the velocity of the slide 48 at a given setting of the crank pin 45. Thus the ordinate 86 at a point 87 describes the slide velocity at the turning angle of the drive pinion 55 corresponding to the point 87.

With the described construction the slide velocity is constant during the working stroke; and there is a quick return. The quick return is characterized by a large downward ordinate.

The dotted line 88 represents the acceleration or rate of change of the velocity. The dot and dash line 90 represents the kinetic energy of the slides at the various turning angles. The kinetic energy is proportional to the square of the velocity, which is always positive. Hence, the composite line 90 extends entirely above the abscissa axis 72 and touches it only at the points of zero velocity.

The diagram of Fig. 10 refers to the motion of the face plate 40 and of the parts rigid with it. The full line curve 89 defines the angular velocity of the face plate at a given constant turning velocity of the drive pinion 55. It is a minimum at the middle of the working stroke, and is largest at and near the middle of the return stroke. Thus, the ordinate 91 of point 92 defines the angular velocity at the turning position corresponding to the abscissa of point 92. The dash-and-dot curve 93 represents the kinetic energy of the face plate, the parts rigid with it, and the members geared to it at a uniform velocity ratio. Member 70 (Fig. 1) is such a member. The ordinates of curve 93 are proportional to the square of the angular velocity of the face plate 40. Thus, the ordinate at point 94, corresponding to point 92, is proportional to the square of the velocity expressed by the ordinate of point 92. Curve 93 has its minimum ordinate in the middle of the working stroke, and its maximum ordinate at the middle of the return stroke. It is generally similar to the curve 90 of Fig. 9.

The inertia effects of the rotary bodies, as illustrated in Fig. 10, however, are independent of the length of stroke. For perfect balance on large machines two different inertia members should be provided. One of these, 74, is adjustable for mass, as described. The other inertia member takes care of the rotary body and has a fixed mass. This other member (not shown) is rigid with a pinion 95 (Figs. 1 and 8) which meshes with face gear 96 (Fig. 1) provided on the opposite side of plate 79.

Because of the similarity of curves 90 and 93 (Figs. 9 and 10) a single inertia member will do well in most cases, an adjustable member like member 74. Its moment of inertia, and its varying ratio gearing are then computed to include the effects of the slides 48, 62 and of the parts which rotate with faceplate 40.

Computation of the mass member and its gearing may be made for a mean length of stroke after the total change in kinetic energy at a given number of cycles per minute has been determined. This change is a given convenient percentage of the minimum kinetic energy of the mass member, for instance, thirty percent. For any given angular velocity of the mass member at its position of mini-

mum kinetic energy, the corresponding moment of inertia can be computed from the given minimum kinetic energy, as well known. Conversely, after assuming a suitable moment of inertia of the mass member, its angular velocity can readily be computed, first for the position of minimum kinetic energy. This position corresponds to the middle of the return stroke, where the kinetic energy of the slides and rotary parts is at its maximum.

As the kinetic energy of the slides and rotary parts changes, it should change on the mass member by the same amount, but in opposite direction, so that the total kinetic energy of the moving parts, including the mass member and the parts attached to it, remains constant. Accordingly, the kinetic energy required on the inertia member is already known for all turning positions of the face plate, and its varying angular velocity can readily be computed. The operative connection between the mass member and the face plate should be such that this varying angular velocity is actually realized.

The face gear 75 has its teeth 97 arranged along a closed curve 98 (Fig. 8) which extends around the gear axis 41' at a varying distance therefrom. This curve lies in a plane which is intermediate the plane top surface of the gear teeth and their plane root surface, and which is perpendicular to the gear axis 41'. It can be considered the pitch plane of the gear. A cylindrical pitch surface of the pinion contacts this pitch plane along a straight line. While the instantaneous ratio between the pinion and face gear changes, there is always a point on said line whose distances from the gear and pinion axes are in the proportion equal to said instantaneous ratio. At this point, the pitch point, the gear and pinion have the same velocity in the considered instant, and true rolling takes place.

As the gear and pinion turn, this point, the pitch point, moves along said straight line, and describes curve 98 on the pitch plane of the gear. If this curve 98, the pitch line of gear 75, were the same as the pitch line 60 of the face gear 56 (Fig. 7), then pinion 76 would turn at uniform velocity, as does drive pinion 55. Pitch line 98 should, therefore, have a different shape from the pitch line 60 (Fig. 7) of gear 56.

Let us first compare pitch lines 98 and 60 having the same maximum distance from the gear axis 41', and having pinions 55 and 76 meshing therewith which have either equal, or unequal, diameters. Then each point 109 of pitch curve 60 has a corresponding point 108 on pitch curve 98 along the same line 109—41' radial of the common axis 41' of the two gears. Point 108 can be determined from the known angular velocity of the mass member in the considered turning position of the face plate. It can readily be demonstrated that the proportion

$$\frac{41'-108}{41'-109}$$

of the radii 41'-108 and 41'-109 is equal to the proportion of the instantaneous angular velocity of the mass member to its maximum angular velocity. The latter corresponds to the pitch point of maximum distance from the gear axis 41'. Since the instantaneous angular velocity required on the mass member is known, the whole pitch curve 98 can readily be determined in the described way from the given pitch curve 60.

This curve 98 also determines the motion transmitted between pinion 76 and gear 75. Their velocity ratio is the proportion between radial distance 41'-108 to the pitch radius of the pinion 76 when a pitch point 108 is in contact with the pitch surface of the pinion. A similar proportion applies to all other pitch points, the proportion of its radial distance from axis 41' to the pitch radius of the pinion. The varying motion gearing can be made in conventional manner, or in the manner described in my pending application Serial No. 431,733 above mentioned.

8 Uniformly rotating face plate

Inertia members may also be used to advantage when the face plate turns at a different varying rate, or at a uniform rate.

The diagram in Fig. 11 relates to a uniformly rotating face plate, and is otherwise similar to the diagram of Fig. 9. A full turn of the face plate 40 is shown with the abscissa denoting the turning angle. The ordinates of full line 115 represent the velocity of the slide 48 at a given turning velocity of the face plate. Dotted line 118, composed of short dashes, describes the acceleration. The dash-and-dot line 120 represents the kinetic energy. All three of these curves are sine curves. The curves 115 and 118 repeat once per turn of the face plate. Curve 120 repeats twice, having two high spots, and two low spots. Accordingly, the gear 121 (Fig. 12), which, in this embodiment of the invention, connects the face plate 40' with the inertia member 122, has a generally elliptical shape. Its teeth 123 are arranged along a pitch curve 124 which has two high spots and two low spots. Its exact shape can be determined with the described procedure.

Mass member 122 is rigidly secured to a pinion 126, that is rotatably journaled in a flanged member 127, which is secured to the machine frame 130. Pinion 126 meshes with face gear 121. The mass member 122 is constructed like the mass members already described. It has discs 131 secured to it. As in the previously described embodiments of the invention, other discs 131 may be added to increase the inertia moment of the mass member 122.

Further design features of the reciprocation device

The gear cutting tool 50 (Figs. 1 and 3), which may be a rack-type tool, is rigidly secured to a holder 132 adapted to swing about a pivot 133 that is mounted in part 48" of slide 48. This part also engages guide rails 52, and is rigidly connected with part 48' of the slide through the part 135 also hinged on pivot 133. It has a rack toothed portion 134 on its under side which engages rack teeth 136 provided on slide part 48'; and it is held in engagement therewith by screws 137 which engage conventional T-slots (not shown) provided in slide part 48'.

To change the distance of slide part 48" from slide part 48', the slide part 48" is first locked vertically on the machine frame in a convenient position, where the counter-balance slide 62 has moved up enough that the screws 137 are accessible. The nuts of the screws are then loosened and part 135 is moved about pivot 133 to disengage its teeth 134 from the rack teeth 136. The machine drive is then operated briefly to move the slide part 48' the required distance from slide 48". Thereafter the part 135 is reconnected with the slide part 48', its teeth 134 having been shifted on the rack 136. After such adjustment the slide part 48" is again unlocked from the machine frame, and the slide 48 is ready to operate.

The tool holder 132 is shown in full lines in Fig. 1 in withdrawn, clapped position. The cutting position of the tool is indicated in dotted lines at 50'. The displacement 60 of the tool and holder 132 to and from cutting position, the clapping, is effected by a pair of cams 140 (Figs. 3 and 4) which act on rollers 141, 142 mounted on the tool holder 132, and which together with said rollers constitute the clapping means. In this way positive movement of the tool between working and clapped positions is attained.

Cams 140 are secured to a transverse shaft 143, to which is also secured a hypoid gear 144, so that the cams and this gear are one rigid unit. Shaft 143 is rotatably mounted on a projection 145 of the slide part 48". Also mounted thereon is a hypoid pinion 146 which meshes with gear 144. The axis of pinion 146 is parallel to the direction of the slide motion. It is driven from a splined shaft 148 which is axially fixed. The pinion slides lengthwise on this shaft during reciprocation of the slide 48. Shaft 148 is coaxial with helical gear 57 and drive pinion

55, and rigid therewith. It is rotatably mounted in the bearings 150, 151, and 152.

If desired, mass balance to a large extent may be provided for the clapping motion by a part 153 shown in dotted lines (Fig. 1) and hinged to pivot 133. Part 153 is constrained to move opposite to the tool holder 132. It moves in when the tool holder moves out, and vice versa. Also, in determining the motion of the mass member 74, or one of the mass members, the energy fluctuations in the clapping parts may be considered.

As described, the inertia member makes up for the torque fluctuations due to the kinetic energy of the parts. It may, however, also be used for other purposes. For instance, it may also be used, if desired, to balance the total supplied torque, and to store up kinetic energy during the return stroke to be delivered during the working stroke. The varying motion required for this purpose on the inertia member can be determined with the above disclosure and the known procedures of the art.

Oscillating device with inertia member

Figs. 13 to 18 inclusive illustrate an application of my inertia member to an oscillating device, and particularly to a machine for grinding or cutting spiral bevel and hypoid pinions in a generating operation. Machines of this kind have an oscillatory cradle 200 rotatably mounted in a machine frame 201. During cutting or grinding the cradle is moved at a uniform rate in time with uniform rotation of the pinion to be produced. The amount of motion varies with different jobs and should be adjustable. On the cradle there is mounted a face-type grinding wheel or cutter 202. The tool may be driven from a motor 203 mounted on the cradle, through a belt 204.

As described in my pending application above mentioned, the motion of the cradle may be obtained through a varying ratio drive consisting of a uniformly rotating pinion 205 meshing with a face gear 206. The gear pair 205, 206 is of the same character as the gear pair 55, 56 illustrated in Fig. 7, and may be identical therewith. A face plate 207 is rigid with the gear 206. The face plate has a slide 210 radially adjustable thereon which carries a crank pin and a roller 208. The roller 208 engages one side of a slot 211 in a slide 212 which is mounted to move in a direction tangential to the cradle 200. An elastic roller 213 engages the roller 208 and the opposite side of slot 211, and serves to take out all backlash, as described in my application above mentioned. Through the radial adjustment of the roller 208 on the face plate the slide 212 can be made to travel uniformly through any desired distance within design limits.

A rack 215 with helical teeth 216 is formed integral with the slide 212, or is rigidly secured thereto. It meshes with a helically-toothed segment 217 that is secured to the cradle 200, and that is angularly adjustable thereon. A roller 218 is eccentrically mounted in an arm 220 that is pivoted on an axis 221 eccentric of the axis of the roller 218. A weight 222 mounted on arm 220 keeps the roller 218 pressed against the rack 215, and maintains the rack in engagement with its segment 217 without backlash.

To take up the end thrust of the inclined teeth of the segment and rack directly, a part 224 (Fig. 14) with a groove 225 is rigidly secured to the rack 215, or is integral therewith. This groove 225 extends in the direction of the rack motion and has plane sides preferably inclined at a small angle to each other, such as five degrees or ten degrees. The sides of the groove are engaged by the conical side surfaces of an arcuate part 226 which is rigidly secured to the segment 217 and which is thereby rigidly secured to the cradle. This arcuate part extends along the segment to the ends of the segment. The profiles of this projection match the profiles of the groove 225, and directly secure the segment 217 to the rack 215 in the direction of the cradle axis and segment axis. In

other words, the axial thrust of the teeth of segment 217 and rack 215 is taken up directly by this engagement.

As the cradle is oscillated at a uniform rate during the working stroke, and has a quick return motion, substantial amounts of kinetic energy are periodically stored up and again released in the moving parts, especially in the cradle when operating at high speed. It is, therefore, important to be able to supply the kinetic energy directly from an inertia member close by, and to absorb it again there and to store it up. This applies especially when the cradle motion is timed with the work rotation, as in the instance referred to.

For this purpose, an inertia member 230 (Figs. 13 and 15), adjustable for mass and weight, is geared to the face plate 207 by means of a cylindrical pinion 231 and a face gear 232. The face gear has a curved pitch line 233 which extends around the gear axis 234 at a varying distance therefrom. The pitch curve 233 contains all the points where true rolling takes place between the pinion 231 and the gear 232 when these points pass the line of contact between the pitch plane of the gear and the cylindrical pitch surface of the pinion.

Pitch curve 233 differs from the pitch curve 235 of the gear 206, which meshes with drive pinion 205. Pitch curve 235 is shown superimposed on pitch curve 233 in Fig. 15 for comparison.

Face gear 232 is integral with a plate 239 that is rigidly secured to the upper end of a shaft 236 which, in turn, is rigidly secured to the face plate 207 and face gear 206. The shaft 236 is journaled at its upper end by means of a bearing 237, and face plate 207 is journaled in the frame 201 of the machine by a bearing 238.

The weight and inertia moment required on the mass member 230 is inversely proportional to the square of its angular velocity, and, therefore, decreases rapidly with increasing angular velocity of the mass member. Accordingly, it is advantageous to use as large a speed-up as practically feasible. In the embodiment illustrated in Figs. 15 and 16 a helical pinion 231 of small diameter is provided, a diameter so small that the pinion would deflect too much under load if it were merely journaled by two bearings placed at its ends. To avoid undue deflection, the pinion is journaled on long, cylindrical rollers 240 (Fig. 16) which bear against the outside cylindrical surface 241 of the tops of the teeth of the pinion, and which are rotatably mounted in cylindrical recesses provided in a stationary part 242. The pinion 231 is further journaled in a bearing 243 (Fig. 15) capable of taking up radial load as well as axial thrust load in both directions.

In the diagrams of Figs. 17 and 18 a complete turn of face plate 207 is considered, the corresponding turning angle of the uniformly rotating drive pinion 205 being plotted in horizontal direction as the abscissa. The middle position corresponds to the middle of the working stroke; the end positions correspond to the middle of the quick return stroke.

Composite line 243 (Fig. 17) is a velocity diagram of the cradle, the ordinates representing the velocity. Curve 244 (Fig. 18) represents the kinetic energy of the cradle and the associated parts, including the slide 212 and face plate 207. It can be determined from the known velocities in the various turning positions of the face plate and of the drive pinion 205 at a given number of turns per minute.

After the diameter of the pinion 231 has been chosen, its angular velocity at the middle of the working stroke can be determined. This is the position of nearly maximum kinetic energy on the inertia member and of nearly minimum kinetic energy on the cradle and associated parts. The minimum kinetic energy of the inertia member differs from the nearly maximum kinetic energy by the amount given by the curve 244, at the ends of the curve, that is, at the middle of the return stroke.

The inertia moment and kinetic energy of the inertia member, and hence its angular velocity, can now be de-

terminated in the way already described. Curve 245 represents the varying velocity of the inertia member as computed from its kinetic energy. Here, however, the horizontal axis 246 corresponds to a definite velocity rather than zero; and the ordinate upward from axis 246 represents a decrease in velocity. The velocity of the inertia member is a minimum at the ends of the diagram where the ordinates are largest. It is at a minimum at the middle of the return stroke.

The known instantaneous velocity of the inertia member makes it possible to determine the pitch curve 233 of face gear 232 in comparison with the pitch curve 235 of face gear 206. This determination is indicated in Fig. 15 for a face gear 232 of the same diameter as face gear 206, where the pitch curves 233 and 235 intersect at a point 248. The radius 234—250 of any other point of the pitch curve 233 is in the same proportion to radius 234—251 of known pitch curve 235, as the velocity of the inertial member in the considered position is to its velocity in the position corresponding to point 248. This is at a turning angle 248—234—251 of the face plate from the last-named position.

The procedure is the same as described with reference to Fig. 8. Here also the size of the drive can be changed if the same proportions are kept.

Figs. 15, 17 and 18 also illustrate a further advantage which can be gained from use of an inertia member constructed according to the present invention. In conventional practice a cradle brake is provided on grinders of the type illustrated in Figs. 13 and 14. Its purpose is to provide a steady resistance load so that the same sides of the teeth of the gears in the timing train remain in contact during the grinding pass, and backlash has no harmful effect on the tooth surface being ground. This conventional procedure consumes energy, and, what is worse, it tends to heat up the cradle and the machine.

With my invention the inertia member can also perform the function of the cradle brake, and do so without consuming any appreciable amount of energy and without affecting the temperature of the cradle. It is then designed to apply a constant load during the grinding pass to the face gear 232. Face gear 232 is rigidly connected with the face plate 207; and backlash between the face plate 207 and the cradle has already been eliminated, since at the rack teeth 216 it is taken out by the roller 218; and at the slot 211 of slide 212 it is removed by elastic roller 213.

To provide a constant torque, an additional constant acceleration should be produced on the mass member during the grinding or cutting operation. A velocity should be added as indicated by curve 255 in Fig. 17. In this figure, increasing ordinates denote increasing velocity. Constant acceleration is indicated by a straight line portion 255' of the velocity graph.

When this varying velocity of the inertia member is added to the velocity indicated by curve 245 in the direction required, a velocity curve 256 results (Fig. 18). This curve intersects curve 245 at the end point and at the middle point 258 where the additional velocity is zero. Any point 260 of curve 256 can be obtained by plotting the ordinate of curve 255 downwardly from the corresponding point 261 of curve 245. Once the velocity curve of the inertia member is known, the procedure is the same as previously described. Indeed, the pitch curve 233 shown in Fig. 15 corresponds to curve 256 (Fig. 18).

If desired, a separate adjustable inertia member may be provided to replace the cradle brake. It could act on teeth provided at the rear 232' (Fig. 13) of plate 239.

Indexing device with inertia member

A further, and very important application of my inertia member, is to indexing devices such as are used for instance in the gear cutting machines, cutter sharpeners, turrets for machine tools, and in other places. It makes

possible a very fast and reliable indexing operation, and does so without disturbing the timing.

One form of index, with inertia member, is illustrated in Figs. 19, 25 and 26. It is an index of the slow start and stop type, that is, an index with a gradual speedup. The type illustrated comprises a Geneva wheel 305 provided with protrusions or teeth 309 equi-angularly spaced about its axis 335. It is intermittently rotated by a driving pin or roller 306 mounted on a shaft 310 (Fig. 25).

The shaft 310 is rotatably mounted in bearings 307, 308, and is rotated at uniform speed by means which include drive gear 311. The latter is splined to shaft 310 and is rigid with it.

The Geneva wheel 305 shown has six ways 312. It is secured to flange 313 of a shaft 314 by screws 315. The shaft is rotatably mounted in bearings 316, 317.

For indexing workpieces having tooth numbers different from the number of ways in the Geneva wheel, the workpieces are mounted on a shaft separate from the shaft 314 and geared to the shaft 314 by change gears. For highest accuracy an index plate 325 is secured to the shaft on which the work is mounted. The axis of this shaft is denoted at 326. A change gear 320 is secured to shaft 314 by a toothed face coupling 321 and screw 322 (Fig. 25); and this change gear meshes with a change gear secured to the shaft which carries the index plate 325. In Fig. 19 only the pitch circles 323, 324 of a pair of change gears are indicated.

The index plate 325 has as many notches 331 (Fig. 19) as there are teeth in the gear to be cut or ground; and the index plate is held stationary during cutting or grinding by a lock dog or pawl 330.

In operation, the Geneva wheel 305 is indexed on each turn of shaft 310, and the shaft 314, to which the Geneva wheel is secured, drives the workshaft or spindle through the change gears, denoted at 323, 324. Assuming clockwise rotation of the shaft 310 in the end view of Fig. 19, the indexing motion is about to start. It starts when the driving pin 306 enters a space 312 between two teeth 309 of the Geneva wheel; and it stops when the driving pin leaves this space. In the time while the Geneva wheel stands still the index plate 325 is locked by the pawl or dog 330. This dog or pawl is carried by a lever 328. The lever is rigidly secured to a shaft 332 whose axis is denoted at 333 (Figs. 20 to 22 inclusive). Axis 333 is parallel to the axis 326 of the index plate and parallel to the axes 334, 335 of the shafts 310 and 314.

Immediately before the indexing motion starts, the pawl 330 should start to release the index plate. The release and reengagement of the pawl is effected by a cam 336 (Fig. 25) which is formed integral with gear 311. Part of the profile 337 of the cam 336 is indicated in dotted lines in Fig. 19. The cam acts on a roller 338 rotatably mounted on a lever 340 which is rigidly secured to the shaft 332. The outward, disengaging motion of the lever 340 and of pawl 328 starts in the position shown in Fig. 19, constrained by the cam profile 337. A spring 341 attached to the pawl lever 328 urges the pawl 330 and lever 340 inwardly, and maintains the roller 338 in contact with the cam. If desired, a second cam may be provided to rotate with cam 336, and to act on a further lever also rigid with shaft 332, to attain positive motion in both directions.

To permit high speed operation of the index mechanism without shock or vibration, a mass member 342 (Fig. 26) is provided. This mass member is rigidly secured to a cylindrical pinion 343 in the manner already described. Its mass is adjustable by taking off or by adding rings 344. The pinion 343, shown here with straight teeth 345, is in mesh with teeth 346 formed on one end face of gear 311. These teeth constitute a face gear 348. In the instance illustrated, the face gear and pinion rotate at uniform speeds in the region where

the driving pin 306 is clear of the Geneva wheel. During the indexing operation, however, uniform motion of the face gear produces a varying motion of the pinion 343. This is achieved by the illustrated arrangement of the teeth 346 of the face gear 348. They are arranged in a circle about the gear axis 334 for the greater part of the circumference, and in that region they represent a conventional face gear. In the portion 350, however, which is active during indexing, they are arranged at a varying distance from the gear axis 334 so that the drive to the mass member 342 is at a varying ratio when that region is in operation.

This drive may be so determined that the kinetic energy of the inertia member 342 and of the parts partaking in the indexing motion, is constant. The kinetic energy of the inertia member, therefore, should depend on the varying kinetic energy of said parts, and, therefore, on their instantaneous angular velocity. The first step, then, is to determine these velocities. This can be done by applying the known principles of kinematics.

To determine the angular velocity of the Geneva wheel in proportion to the angular velocity of shaft 310, different positions of the center of the driving pin 306 are considered. In a position such as 351 (Fig. 19) the pin center moves in a radial direction 351—335 relative to the Geneva wheel. The normal 351—352 to the direction of this path intersects the line of centers 334—335 in the instantaneous center 352 of relative motion. The instantaneous ratio between the angular velocity of the Geneva wheel and of the shaft 310 is then equal to the ratio of the distances 334—352 and 352—335 of instantaneous center 352 from the two axes. This determines the instantaneous angular velocity of the Geneva wheel from the given and constant angular velocity of shaft 310. The angular velocities at other turning positions of the driving pin 306 are similarly determined so that finally the distribution of the angular velocity of the Geneva wheel is determined for the entire indexing motion. Knowing the instantaneous velocity, we can readily compute the instantaneous kinetic energy of the indexed parts at a given angular velocity of shaft 310 and a given ratio of the pitch circles 323, 324. The moment of inertia of the parts is, of course, also known and used.

A curve may be plotted, which gives the varying kinetic energy of the indexed parts in terms of the turning angle of shaft 310. This curve is similar in character to curve 244 of Fig. 18, but not in shape.

The kinetic energy of the inertia member should vary like this curve, but in a negative manner, so that the largest kinetic energy given by such a curve corresponds to the smallest kinetic energy of the inertia member. This is as described for the other applications of the inertia member. Here, however, the conditions are somewhat simpler because the shaft 310 with the driving pin 306 rotates at uniform speed.

After assuming the kinetic energy of the inertia member in one position, its varying kinetic energy during the entire indexing cycle is determined by the said curve, and with it its varying angular velocity can be computed. The varying ratio gearing 343, 348 (Fig. 26) can thus be determined with the directions given.

If desired, the procedure may be exactly as described with reference to Fig. 8 when a pitch circle concentric with the face gear is substituted for the pitch curve 60 of Fig. 8.

An inertia member determined for a given speed will give perfect balance of the kinetic energy at all speeds. However, when the ratio of the pitch circles 323, 324 is changed, that is, the angular pitch of the work to be indexed is changed, or when the inertia moments are changed, a different moment of inertia may be required on the mass member, as readily understood. Fortunately, the larger gears with more teeth and smaller angular pitch have also larger moments of inertia, so that some com-

pensation is effected thereby. Thus, the moments of inertia required on the mass member are within reasonable limits.

The counter-rotating Geneva wheel and index plate, and the parts rigid with them, provide some degree of dynamic mass balance. Perfect dynamic mass balance exists when the moments of inertia of the two rotary bodies are proportional to the diameters of the pitch circles 323, 324. It can be provided, if desired for high speed operation, by adding to the moment of inertia of one of the two bodies, if necessary.

Index plates

Because of the high speed operation possible with an index mechanism built according to the present invention, it is also advisable to improve the index plates and their pawls, so that they stand up without wear under continued high speed operation.

The function of index plates is not merely a static one; they also have to give a slight correcting action; they have to supply a small displacement from a nearly correct position to a final accurate position at the end of each indexing operation. As a pawl moves into locking engagement with a slot of the index plate, it ordinarily finds the index plate slightly off position. In the engaging process, the pawl engages the sides of the slot of the index plate, moves the index plate slightly, and sets the plate right.

Conventional pawls do not apply this last setting touch in the best manner. Fig. 23 shows a conventional pawl 400 entering a slot 401 in index plate 402. The slot and the pawl have straight sides 403, 404, respectively, which include a moderate angle with one another. As the pawl moves inwardly about its axis 405, it also tips so that its sides 404 no longer fit the directions of the sides 403 of the slot. Should the index plate be turned about its axis 406 into contact with the pawl, contact would be made at a corner, either at the corner 407 of a tooth of the index plate or at the corner 408 of the pawl. This is not a good contact, since it concentrates the loads at the corners. Moreover, it is sliding contact and tends to produce wear, and thereby inaccuracy, if used long enough.

In actuality, contact may be made in a position of the pawl closer to the bottom of slot 401. But even there contact is made with a corner 407 of a tooth of the plate or a corner 408 of the pawl. Fig. 23 also shows how unevenly the sides 404 of the pawl 400 enter into engagement with the sides 403 of the slot 401.

In accordance with the present invention a shape is provided on the slot and the pawl such that the separation between the slot and pawl is more nearly equal along the whole length of the mating sides of the slot and pawl; and especially a shape such that in the positions near full engagement the side of the pawl is still capable of contacting with the adjacent side of the slot. Contact concentrated at a corner is thereby avoided; and the final touch between the pawl and the slot, to give the last correcting action, is made between sides of the two parts rather than with a corner. This spreads out the contact; contact stresses are low; and wear is prevented or sharply reduced.

To this end curved profiles 410, 411 are provided on the pawl 330 and on the sides of the slots 331 of the index plate. The outer profile 410 of the pawl is convex, its inner profile 411 is concave. The mating profiles of the slot 331 are concave and convex, respectively.

The profiles may be made circular arcs. When the mating profiles are fully matched and capable of having contact along their entire length in full depth position, they are what may be called "basic" profiles. The basic profile 410 is a circular arc centered at 415 (Fig. 19). The basic profile 411 is a circular arc centered at 416. Both centers 415 and 416 lie on a connecting line 326—333 of the axes of the index plate and of the pawl.

When the pawl 330 turns on its axis 333, and the index plate turns with it to retain contact, the center 415, or 416, of each pair of contact profiles moves in the same direction, that is, in a direction perpendicular to line 326—333. At small displacements the centers of a pair of contacting profiles do not tend to separate. Thus, the profiles tend to remain in contact with each other on their sides.

Fig. 20 shows how a pawl 330 recedes from its slot 331. Pawl 330 has been rocked about its axis 333 the same amount as the pawl 400 of Fig. 23. The centers of the pawl profile have been turned to positions 415', 416'. The slot profiles are still at 415, 416. It is readily seen how much better the corresponding pawl and slot profiles remain in alignment with each other.

Fig. 21 shows the same position of the pawl as Fig. 20; but the index plate 325 has been turned on its axis 326 so that contact is made on the side 411 of the pawl. The contact is near perfect, not angular as in Fig. 23.

Fig. 22 also shows the same position of the pawl as Figs. 20 and 21; but here the index plate 325 has been turned on its axis 326 so that contact is made on the side 410 of the pawl. Here, also, the contact is near perfect.

Instead of using fully matched profiles of exactly the same radius on the pawl profile and the mating slot profile, some ease-off may be provided between them, as is customary also on gear teeth. The convex profile then has a slightly smaller radius than the mating concave profile. Thus, on the side 410, the convex pawl profile may be centered at 415a (Fig. 19), while the mating concave profile is centered at 415b. The two centers are preferably located on opposite sides of the center 415 of the basic profile.

One application of the indexing device of the present invention is in a gear generator of the gear shaper type, where the cutting tool is of gear form. In Fig. 24 such a cutting tool is indicated at 300 in engagement with a gear blank 301. As the cutter reciprocates along its axis 303 it also turns very slowly about this axis, while the gear blank turns on its own axis 302 as though the gear being cut were meshing with and rolling on a gear represented by the reciprocating cutter 300. In this operation each tooth of the cutter takes a good many cuts before it leaves the cutting zone.

In such a machine, the speed of cutting, or the thickness of the chips, is limited by the high temperature caused at the cutting face adjacent the cutting edges. Too high a temperature, and a prolonged high temperature, are detrimental to the tool, because under these conditions the tool will require frequent resharpening and will be used up rapidly.

With a fast enough index, as is made possible by the present invention, the cutter can be indexed one tooth after every stroke. After each cutting stroke it is disengaged completely from the work and indexed during the return stroke. Then no high temperatures develop at the cutting face adjacent the cutting edges, and whatever temperatures develop, they are not prolonged. Higher cutting speeds can be used without detriment to the tool, or higher feed rates, or both. There is a marked gain of efficiency in the gear shaping process in general. In some cases a feed rate may be used such that the cutter makes a complete turn stepwise per tooth of the gear blank.

Another application of the indexing mechanism of the present invention is to plunge grinding. A fast index will extend the range of plunge grinding and the quality of the product. In plunge grinding, contact between the grinding wheel and the work is not merely along a line at a time but on a whole surface area. For any but short areas the grinding wheel tends to load up in plunge grinding, and to produce a poor finish. With a fast index, the grinding time can be shortened, and repeated more often, so that less wheel loading occurs and a better

finish is produced. Longer areas can be ground too in this manner without incurring a poor finish, and without burns.

Milling cutters, helical shaper tools, etc. can be sharpened by plunge grinding. Also, toothed couplings and clutches, and especially face couplings and form gears, can be plunge ground when a fast index is provided. The use of many fast strokes of short duration has the further advantage that the produced tooth surfaces or cutting faces are alike to the highest degree. There is very little wheel wear around the work because of the short grinding engagement. In gear cutting and gear grinding a fast index permits the work to be indexed after every cutting pass or grinding pass.

Modified inertia member

The present invention is by no means limited to the form of inertia member heretofore described. Broadly an inertia member can be constructed according to the

present invention which is capable of periodically changing its kinetic energy while the shaft to which it is operatively connected continues to rotate uniformly. There are many ways to effect this change in kinetic energy. The preferred way is to change the angular velocity of the inertia member periodically. However, it would also be possible to change its moment of inertia periodically, and leave its angular velocity constant. Even where its angular velocity is varied, the variation can be achieved with other than a varying-ratio gear pair.

Fig. 27 shows part of an indexing device similar to the one illustrated in Fig. 25. Here, too, the index motion is operated by a driving pin 306'. This pin is rigid with shaft 360 that is rotatably mounted in bearings 357, 358. The shaft 360 is driven through gear 361. It has helical grooves 362. These grooves are adapted to receive balls 363. The grooves and the balls 363 serve as a mounting for a cam member 364 so that the cam member can move axially along the helical grooves 362 with little friction. In this axial motion the balls roll inside the hub of member 364 from one end disc 365 of the hub to the other 366. They fill the length of the hub only partly so that they can roll in operation.

The outer sides 367, 368 of the member 364 are cam surfaces adapted to engage a pair of tapered rollers 370, 371 mounted on stationary pins 372. As the member 364 is rotated through shaft 360 it is constrained to move axially by the rollers 370, 371. Member 364 has helical teeth 373 (Fig. 28) on its outside surface. These helical teeth are of a hand opposite to the hand of the helical grooves 362. A helical pinion 374 meshes with these teeth near the position of the rollers 370, 371, see also Fig. 28. Pinion 374 is rotatably mounted in anti-friction bearings, of which one is shown in Fig. 27 at 375. Rigidly secured to the pinion 374 is a mass member 376 adjustable for mass, that is, having removable rings 378.

The speed of the axial displacement of the member 364 affects the rotational speed of the mass member 376 so that it can be made to turn at a varying speed during the indexing motion while the shaft 360 turns at a constant speed.

Since the rotational speeds required on the mass member 376 are known for each turning angle of the shaft 360, and can be determined as described, and since consequently the corresponding turning positions of the mass member are also known, the axial displacement to be produced by the engagement of the cam 364 with the rollers 370, 371 can be determined with the knowledge of the art.

For maximum effect helical grooves 362 and helical teeth 373 are used. However, either the grooves, or the teeth 373, may be straight. Thus, straight grooves extending along the axis of shaft 360 could be used instead of helical grooves 362.

Fig. 29 is a velocity diagram of a mass member in terms of the turning angle of the shaft which contains

the driving pin 306' or 306. An increase in angular velocity is plotted upwardly; a decrease downwardly in this diagram. The heavy horizontal line 380 represents an average angular velocity. The vertical line 381 at the left end corresponds to the start of the index motion, as does the line 381' at the right end, their horizontal distance representing a full turn of the shaft with the driving pin. Lines 382 and 383 represent the middle and end of the indexing motion, respectively.

The determination of the inertia members, as described thus far, has been based on a velocity distribution as indicated in dotted lines 384. Here the angular velocity dropped from a high value at 381 to a low value at 382; and then rose again to the same high value as at 381, reaching it at 383. Then it remained constant between indexing motions. This is considered the best distribution when the friction is negligible or nearly so.

It is also possible, however, to consider friction, and to take account of the fact that some of the energy is used up and is lost in the transfer of the kinetic energy between the mass member and the indexing parts. The aim is to have minimum torque fluctuation in the drive to the index.

Considering friction, the inertia member has to give up somewhat more kinetic energy than is received by the indexed parts. As indicated by the velocity curve 385 shown in full lines, the angular velocity of the inertia member drops from a maximum at 381 to a value at 382 lower than with the dotted line 384; and at 383 its angular velocity is not up yet to the maximum value. The angular velocity increases gradually in the period between indexing motions, to reach the maximum value again at 381'. Gearing to produce this or any other velocity distribution can be determined and made without further instructions.

Horizontal line 380 represents the average angular velocity which the inertia would have without axial motion of the cam member 364.

Many turns of drive shaft between indexing

In the indexing device thus far described, the drive shaft 310 (Fig. 25), which carries the driving pin 306, effects an indexing motion at each of its turns. The embodiment now to be described with reference to Figs. 30 to 35 inclusive indexes less frequently. Here the shaft 510 with the driving pin 506 performs a plurality of turns between indexing. The number of turns is variable. It can be set to any desired number, for instance, the tooth number of a gear.

The driving pin 506 of the uniformly rotating shaft 510 is ordinarily out of reach of the Geneva wheel 505. For indexing, however, the shaft 510 advances axially to the proper depth position to engage in a slot 511 of the Geneva wheel. Indexing itself then takes place as previously described. After indexing, the shaft 510 recedes axially to its idling position where its driving pin 506 is clear of the Geneva wheel.

The shaft 510 has an extension 509 rigid therewith which carries a pinion 508 and a ball bearing 507 adapted to take axial thrust in both directions. The outer race of this ball bearing is secured to a generally tubular slide 512 which is angularly stationary, and which is urged by a strong spring 513 to the right in Fig. 30. Most of the time a catch 514 (Fig. 33) prevents such displacement, and keeps the slide 512, and with it the shaft 510, in the idling position shown. Any suitable known catch may be used. The catch shown consists of a diametral boss formed on the rod 515 intermediate the ends of this rod. This boss seats in a cooperating recess provided on slide 512. Rod 515 also has an integral tubular portion 516 above boss 514, and is axially movable. The catch or boss 514 is kept in engagement with its recess on slide 512 by a spring 517 which extends into said tubular portion 516.

In the embodiment illustrated, a cam 518 operates to release the catch 514. This cam is geared to shaft 510 at the desired ratio of the number of turns of shaft 510

- per indexing cycle. If, for instance, thirty-six turns are desired, the ratio between the gears 520, 521, 522 and 508 (Fig. 32), is thirty-six to one, so that there are thirty-six turns of the shaft 510 to one turn of the cam 518. 5 The cam 518 and the change gear 520 coaxial with it are rigidly secured to a circular slide 524 turning on a fixed stud 525. Gears 521 and 522 are mounted on an intermediate shaft whose axis is denoted at 523. Circular slide 524 is mounted on a fixed part 531 of the machine. 10 It is secured in any adjusted position thereon by bolts 532. The use of a circular slide makes a compact construction possible, in spite of the large diameter of the cam 518 and gear 520.

As the cam 518 rotates, its projection 526 (Fig. 33) 15 lifts the rod 515 and releases the catch 514. The shaft 510 then moves forward (to the right in Fig. 30) under the urge of the spring 513. In this motion it is guided by a stationary groove 527 (Fig. 31) in part 531. This groove is engaged by the spherical front face 529 of the driving pin 506. The driving pin reaches full depth position just prior to the start of the indexing motion. After completion of the indexing motion, the groove 527 forces the driving pin and shaft 510 back axially close to its idling position. The catch 514 then snaps back again into locking position as the long idling run starts.

While a mechanical release for the catch has been described, any suitable known other kind of release could be used also, as, for instance, a solenoid.

The drive from the Geneva wheel 505 to the index 30 plate may be as illustrated in Fig. 19. The outward or releasing motion of the lever 528, which carries the locking pawl (not shown), is effected by a lever 540 rigidly secured thereto, and cooperating with a cam 536 formed here at the front end of the shaft 510. Cam 536 is within 35 reach of lever 540 only at and near the full depth, forward position of shaft 510. Another lever 553, also rigidly connected with the lever 528, maintains positive locking of the index plate during the idling period. It leans against the end 510' (Figs. 30 and 31) of shaft 510.

40 In the advanced position of the shaft 510, this end is out of reach of the lever 553, and therefore permits inward motion of the lever. In the idling position, it locks the lever in place.

A pair of coaxial, integral gears 554, 555 are rigidly 45 secured to the shaft 510 as by a bolt passing through a hole 556 of the shaft. Gear 554 is a conventional spur gear, adapted to transmit uniform motion. Gear 555 is identical with gear 554 on most of its circumference. On the remainder, the portion, which corresponds to indexing and which is one-hundred twenty degrees in extent in the example illustrated, it is a varying ratio gear. The two gears 554 and 555 are adapted to mesh with a conventional spur pinion 558 (Fig. 35). Spur pinion 558 is formed integral with a shaft 560 (Fig. 30), which is rotatably mounted in bearings 561, 562. A mass member 536' is rigidly secured to shaft 560. For convenience the shaft 560 is shown as lying in the plane of the axes of the Geneva wheel 505 and of shaft 510. It may, however, be located outside this plane so that it clears 55 lever 553 (Fig. 31).

55 Gear 555 and pinion 558 are shown in Fig. 35 in a view along their axes. The pitch curve 563 of the gear 555 is the locus of the points on the gear where true rolling takes place between the gear and the pinion 558, when the points are on the line of centers. The shown position corresponds to the middle of the indexing motion. 564 is the pitch point in this position. The varying ratio pitch curve portion 565—564—566 joins the pitch circle 568 of the uniform motion portion at points 565 and 566. These correspond to the ends of the indexing motion.

An obvious way of producing gear 555, and particularly its varying ratio portion 565—566, is by generating the pinion with a reciprocating gear type cutter which thereby represents the pinion, and by turning the gear

blank and the cutter about their axes at the required changing ratios desired between the pinion and the gear. The required shape of the teeth is then automatically formed on the gear blank. In the portion adjacent point 564 the teeth 570' of the gear 555 have an increased pressure angle. In the uniform motion portion the teeth 570 of the gear have conventional shape.

Uniform motion is applied to the gear 554 by a pinion 571 (Fig. 30) which is made extra long so that it keeps in mesh when the gear 554 moves with shaft 510 to the right for indexing.

Pinion 558 of the mass member 536' is also made extra long; but it has a different axial position. As the shaft 510 moves to the right, the pinion 558 moves out of engagement with gear 554, and moves into engagement with gear 555. In the full depth position, when indexing takes place, it is wholly engaged with gear 555 only. During indexing, the gear 555 and the pinion 558 represents a varying ratio drive, acting like those described. After indexing, the shaft 510 moves back to idling position again so that pinion 558 meshes again with gear 554 at a constant ratio. The mass member is, therefore, driven at a uniform velocity when the driving member 536 of the Geneva mechanism is idling; and it is driven at a varying rate when the driving member is functioning through pin 506 to drive the Geneva wheel 505 and effect indexing.

Fig. 36 illustrates a modified way of changing the effect of the mass member. This is done by gearing rather than by a change of mass. The mass of member 536' secured to shaft 560' is embodied as a gear 572 which meshes with a change gear 573 rigidly secured to another mass member 574. The latter is rotatably mounted on slide 575 that is adjustable toward and away from the shaft 560'.

Here the inertia moments of the members 536' and 574 remain unchanged. The inertia effect is changed by substituting another change gear 573. A smaller gear 573 produces a higher speed on mass member 574 and increases the inertia effect. A larger gear 573 decreases the inertia effect. As gear 573 is changed, the slide 575 is adjusted to set the new gear 573 into full mesh with gear 572.

While I have discussed in detail applications of my inertia member to the machine tool field, it should be understood that these are only examples, and that the invention is broadly applicable to torque equalization. In fact, while the invention has been described in connection with several different embodiments thereof, it will be understood that it is capable of further modification, and this application is intended to cover any variations, uses, or adaptations of the invention following, in general, the principles of the invention and including such departures from the present disclosure as come within known or customary practice in the art to which the invention pertains, and as may be applied to the essential features hereinbefore set forth, and as fall within the scope of the invention or the limits of the appended claims.

Having thus described my invention, what I claim is:

1. In combination, a rotary driving part, means for driving said part at a uniform speed, and an inertia mechanism for steadyng said rotary driving part under a periodically-repeating, varying load, said inertia mechanism comprising a rotary mass member, and means operatively connecting said mass member to said rotary driving part, said mass member being connected to the means for driving said rotary driving part only through said rotary driving part, said connecting means constraining said mass member to turn at a predetermined varying speed ratio while said rotary driving part rotates at a uniform speed, whereby said mass member periodically transmits a portion of its kinetic energy to said rotary driving part and periodically receives it back therefrom.

2. In combination, a rotary driving part which is sub-

ject to a periodically-repeating load, means for driving said rotary driving part, and an inertia mechanism for storing energy to be interchanged with said rotary driving part, comprising a rotary mass member, and gearing for connecting said mass member with said rotary driving part to produce a predetermined varying speed ratio between said mass member and said rotary driving part, said gearing including a pair of varying ratio gears, and said mass member being connected to said driving means only through said rotary driving part.

3. In combination, a rotary driving part, means for driving said part, and an inertia mechanism for storing energy to be interchanged with said rotary driving part comprising a rotary mass member, and gearing for constantly connecting said mass member with said rotary driving part to produce a predetermined varying speed ratio between said mass member and said rotary driving part, said gearing including a pair of varying ratio gears consisting of a cylindrical pinion and a face gear having its teeth arranged at a varying distance from its axis.

4. In combination, a rotary driving part, means for driving said part, and an inertia mechanism for storing energy to be interchanged with said rotary driving part under a periodically-repeating, varying load, comprising a rotary mass member connected with said driving means only through said rotary driving part, and a single pair of toothed varying-ratio gears operatively connecting said mass member with said rotary driving part, said mass member being connected with said driving means only through said rotary driving part.

5. In combination, a rotary part, a rotary mass member, means for rotating said part, and means for connecting said mass member to said rotary part to transmit a predetermined motion at a varying speed between said mass member and said rotary part whereby said mass member periodically transmits a portion of its kinetic energy to said rotary part and periodically receives it back therefrom, said mass member being connected to said rotating means only through said rotary part.

6. An inertia member for storing energy to be interchanged with a rotary part adapted to effect periodically-repeating motion on a further part for steadyng the motion of said rotary part, comprising a rotary mass member, toothed uniform motion gearing constantly connecting said mass member with said rotary part, a cam operatively connected with said rotary part, and an operative connection between said cam and said mass member operable to change the speed ratio of said mass member as compared with said part.

7. An inertia member for storing energy to be interchanged with a rotary part adapted to effect periodically-repeating, varying motion on a further part of steadyng the motion of said rotary part, comprising a rotary mass member, a cam mounted on said rotary part to rotate therewith and to be axially movable thereon, a stationary abutment adapted to engage said cam to cause an axial displacement thereof while in engagement therewith, a helical gear secured to said cam member, and an axially-fixed helical pinion meshing with said gear and fixedly secured to said mass member, whereby axial displacement of said cam changes the speed of said mass member.

8. An inertia member for storing energy to be interchanged with a rotary part adapted to effect periodically-repeating motion, comprising a rotary mass member having a plurality of discs removably secured thereto and changeable to change the inertia of said mass member, and a pair of varying ratio gears for operatively connecting said mass member to said part at a predetermined varying speed ratio, said pair of gears consisting of a pinion rigid with said mass member, and a gear rigid with said rotary part.

9. A reciprocating device comprising a rotary crank plate having a crank pin radially adjustable thereon, a slide, means connecting said crank pin to said slide to reciprocate said slide upon rotation of said crank plate,

means for rotating said crank plate, a rotary mass member, and a pair of varying ratio gears operatively connecting said mass member and said crank plate to effect a predetermined varying speed ratio, said gears consisting of a pinion rigid with said mass member and of a gear rigid with said crank plate.

10. A reciprocating device comprising a rotary crank plate having a crank pin radially adjustable thereon, a slide, means connecting said crank pin to said slide to reciprocate said slide upon rotation of said crank plate, means for rotating said crank plate, a rotary mass member, a pair of varying ratio gears operatively connecting said mass member and said crank plate to effect a predetermined varying speed ratio, said gears consisting of a pinion rigid with said mass member and of a gear rigid with said crank plate, a counter-balance slide, and means for moving said counter-balance slide in the opposite direction to the first-named slide upon movement of said first-named slide in either direction.

11. A reciprocating device comprising a rotary crank plate having a crank pin radially adjustable thereon, a slide having a transverse slot therein, a part rotatably mounted on said crank pin and engaging in said slot to reciprocate said slide on rotation of said crank plate, a counter-balancing slide, toothed gearing connecting the two slides and constraining said counter-balancing slide to move oppositely to the first-named slide in direct proportion to the motion of said first-named slide, means for rotating said crank plate, a rotary inertia member, and a pair of varying ratio gears for operatively connecting said inertia member and said crank plate to effect a predetermined varying speed ratio, said pair of gears consisting of a pinion rigid with said inertia member and a gear rigid with said crank plate and provided with more teeth than said pinion.

12. A reciprocating device comprising a rotary crank plate having a crank pin radially adjustable thereon, a slide having a transverse slot therein, a part rotatably mounted on said crank pin and engaging in said slot to reciprocate said slide on rotation of said crank plate, a counter-balancing slide, toothed gearing connecting the two slides and constraining said counter-balancing slide to move oppositely to the first-named slide in direct proportion to the motion of said first-named slide, means for rotating said crank plate in such way as to attain more nearly uniform slide motion in one direction, at least one rotary inertia member with adjustable moment of inertia, and a pair of varying ratio gears for operatively connecting said inertia member and said crank plate to effect a predetermined varying speed ratio, said pair of gears consisting of a cylindrical pinion rigid with said inertia member and a gear rigid with said crank plate and having more teeth than said pinion.

13. A reciprocating device comprising a rotary crank plate having a crank pin radially adjustable thereon, a slide having a transverse slot therein, a part rotatably mounted on said crank pin and engaging in said slot to reciprocate said slide on rotation of said crank plate, a counter-balancing slide, toothed gearing connecting the two slides and constraining said counter-balancing slide to move oppositely to the first-named slide in direct proportion to the motion of said first-named slide, a cylindrical pinion and a mating face gear for imparting varying motion to said face plate to attain a uniform velocity of said slide during movement of said slide in one direction, at least one rotary inertia member with adjustable moment of inertia, and a pair of varying ratio gears for operatively connecting said inertia member and said crank plate to effect a predetermined varying speed ratio, said pair of gears consisting of a cylindrical pinion rigid with said inertia member, and of a face gear rigid with said crank plate.

14. In combination, a rotary crank plate having a crank pin radially adjustable thereon, a slide having a transverse straight slot, a part rotatably mounted on said crank

pin and engaging in said slot to reciprocate said slide on rotation of said crank plate, means for imparting varying rotary motion to said crank plate so that said slide is moved at an approximately uniform rate in one direction, an inertia member, and a pair of varying ratio gears for operatively connecting said inertia member and said crank plate, an oscillatory member, and means for oscillating said member in direct proportion to the motion of said slide.

15. In combination, a rotary crank plate having a crank pin radially adjustable thereon, a slide having a transverse straight slot, a part rotatably mounted on said crank pin and engaging in said slot to reciprocate said slide on rotation of said crank plate, means for imparting varying rotary motion to said crank plate so that said slide is moved at an approximately uniform rate in one direction, a rotary inertia member, a pair of varying ratio gears for operatively connecting said inertia member to said crank plate in such way that the inertia member is accelerated during said approximately uniform motion, an oscillatory member, and means for oscillating said member in direct proportion to the motion of said slide.

16. In combination, a rotary crank plate having a crank pin radially adjustable thereon, a slide having a transverse straight slot, a part rotatably mounted on said crank pin and engaging in said slot to reciprocate said slide on rotation of said crank plate, means for imparting varying rotary motion to said crank plate so that said slide is moved at an approximately uniform rate in one direction, a rotary inertia member, and gear means for operatively connecting said inertia member and said crank plate at a predetermined varying speed ratio in such way that said inertia member is accelerated during said approximately uniform motion.

17. In combination, a rotary part, means for rotating said part, an index plate, means for transmitting intermittent motion from said part to said index plate in which the index plate is accelerated and decelerated, and a rotary inertia member connected to said part to slow down during acceleration of said index plate and to speed up again during its deceleration as compared with the rotation of said part.

18. In combination, a rotary part, means for rotating said part, an index plate, means for transmitting intermittent motion from said part to said index plate in which the index plate is accelerated and decelerated, and a rotary inertia member, and gearing for connecting said inertia member and said part, said gearing being adapted to slow down the inertia member during acceleration of said index plate and to speed it up again during its deceleration, as compared with the rotation of said part.

19. In combination, a rotary part, means for rotating said part, an index plate, means for transmitting intermittent motion from said part to said index plate in which the index plate is accelerated and decelerated, and a rotary inertia member, a pair of varying-ratio gears connecting said part and said inertia member, one of said pair of gears being rigid with said part and the other of said pair of gears being a cylindrical pinion rigid with said inertia member, said gears being timed to slow down the inertia member during acceleration of said index plate and to speed it up again during its deceleration.

20. In combination, a rotary part, means for rotating said part, an index plate, means for transmitting intermittent motion from said part to said index plate in which the index plate is accelerated and decelerated, a rotary inertia member, a pair of gears connecting said part and said inertia member and constraining said inertia member to rotate at a larger speed of rotation than said part, one member of said gear pair being rigid with said part and the other member of said gear pair being rigid with said inertia member.

21. In combination, a slide, rotary means for imparting a reciprocatory movement to said slide at a varying velocity, means for driving said rotary means, a rotary mass

member, and means operatively connecting said mass member to said rotary means for transmitting motion at a predetermined varying velocity ratio interchangeably between said rotary means and said mass member.

22. In combination, a slide, means for reciprocating said slide comprising a rotary crank plate, a crank pin radially adjustable thereon, and means for rotating said crank plate, a rotary mass member, and means operatively connecting said mass member to said crank plate to transmit motion at a predetermined varying velocity ratio between said crank plate and said mass member, said mass member being connected to said rotating means only through said crank plate. 10

23. In combination, a rotary driving part, means for rotating said part at an approximately uniform speed, a driven member, means for imparting periodically repeating motion from said part to said member, a rotary mass element, an operative connection between said element and said part to change the kinetic energy of said element periodically at the period of said repeating motion upon uniform rotation of said part, said mass element being connected to said part so that kinetic energy is periodically transmitted from said element to said part and received from said part, to steady said part, said element being connected to said rotating means only through said part. 15 20

24. In combination, a workpiece, a rotary driving part, means for rotating said part in time with said workpiece, a driven member, means for imparting periodically repeating motion from said part to said driven member, tool means mounted on said member for engagement with said workpiece, a rotary mass element, an operative connec- 25 30

tion between said element and said part to produce a predetermined varying speed ratio between them so as to change the kinetic energy of said element periodically at the period of said repeating motion upon uniform rotation of said part, said mass element being connected to said part so that kinetic energy is periodically transmitted from said element to said part and received from said part, to steady said part.
